UNITED STATES PATENT OFFICE.

ESPIRIDION HIPOLITO, OF LOS ANGELES, CALIFORNIA, ASSIGNOR TO THE HIPOLITO SCREEN AND SASH COMPANY, OF LOS ANGELES, CALIFORNIA, A CORPORATION OF CALIFORNIA.

BORING-MACHINE.

SPECIFICATION forming part of Letters Patent No. 738,612, dated September 8, 1903.

Application filed April 24, 1901. Serial No. 57,334. (No model.)

To all whom it may concern:

Be it known that I, ESPIRIDION HIPOLITO, a citizen of the United States, residing at Los Angeles, in the county of Los Angeles and State of California, have invented a new and useful Boring-Machine, of which the following is a specification.

The object of this invention is to provide an extremely simple and efficient boring-machine and to facilitate the boring of holes in articles to be bored.

My invention is especially applicable for boring dowel-holes in the stiles and other members of window-sash, screen-frames, and doors in which a number of uniformly-spaced holes are to be bored; but it is applicable for other uses.

My invention is applicable for multiple boring-machines in which a plurality of boring-bits are employed; but in view of the fact that it is not new in the art to simultaneously operate a plurality of boring-bits I shall illustrate my invention herein simply as applied with a single boring-bit.

The accompanying drawings illustrate my invention as applied in a machine for boring dowel-holes in the stiles and other members of window-sash, screen-frames, and doors with a single boring-bit.

Figure I is a perspective view of my invention ready for operation. Parts are broken away to contract the view. Fig. II is a front elevation of the carrier and its support, parts of which are broken away to contract the view. Fig. III is a sectional plan of the machine on line indicated by III III, Fig. IV. Fig. IV is a side elevation, partly in section, on line IV IV, Fig. III. The carriage is shown depressed. The parts are broken to contract the view. Fig. V is a vertical sectional detail to illustrate the resilient depressible stop. Fig. VI is a fragmental detail of the spring-stop z' . Fig. VII is a fragmental view of the floor of the carriage with the sliding stop therein. Fig. VIII is a fragmental sectional view on line VIII VIII, Fig. VII.

My newly-invented boring-machine comprises an upwardly-directed vertical rotary boring-bit a , fastened to a stationary upright rotary shaft b , a vertically-moving carriage c

to carry the article to be bored and furnished with a suitable passage d for the bit, and suitable means for operating the carriage vertically. Said means may be of any desired character; but in the drawings I have shown a resilient support composed of springs e , extending between two yokes f g , one of which, f , is pivotally connected with the carrier h of the carriage. Preferably the pivotal connection between the yoke f and the carrier h of the carriage is formed by a link i , a bolt j fastening the link i to the carrier h and a bolt k fastening the link i to the yoke f . The upper yoke g is pivotally fastened to a hanging support, such as the link m , by means of a pivot-bolt n . The hanging-link m is furnished with a series of holes o , by means of which the yoke g may be mounted at a higher or lower level, as desired, for increasing or decreasing the tension of the springs e in order to adjust the machine for easy operation with articles of different weights. I do not limit myself to such means of adjusting the tension of the springs. The boring-bit a extends upward coaxial of the rotating shaft b , and the resilient support e allows the carriage to be depressed to bring the article to be bored into contact with the bit.

p indicates vertical guideways for the carrier h of the carriage.

q indicates a connecting-rod connecting the carrier with a treadle r . The treadle r , rod q , and the springs e constitute the means for operating the carriage c vertically.

s indicates the shelf or floor of the carriage or supporting device for supporting the article to be bored.

t indicates a gage plate or wall against which the article to be bored will be held in the process of boring.

u indicates a clamping-cam pivoted to the floor s of the carriage and adapted to clamp the article to be bored firmly against the gage-bar t .

v indicates suitable supports upon which the gage-bar t is adjustable horizontally. These supports are preferably formed, as shown, of horizontal arms which are fastened to and project from the carrier h .

w indicates set-screws by means of which

the gage-bar *t* is adjustably fastened upon the pins or supports *v*.

The support-pins *v* are clamped to the vertically-moving carrier *h* by means of set-screws *x*.

The front face of the gage-bar *t* is preferably corrugated with sharp horizontal corrugations, as shown in Fig. IV, and the clamping-cam *u* is likewise furnished with horizontal corrugations. When the article to be bored is clamped between the gage-bar *t* and the clamping-cam *u*, the corrugations will hold the article to the carriage, so that as the carriage is lowered the article to be bored will be forcibly carried downward to engage the upper cutting end of the rotary cutting-bit. By arranging the corrugations horizontally they will engage with the wood lengthwise of the grain, thereby entering it more readily and affording a better hold, and at the same time they will do less damage to the wood than where the indentations are made across the grain. It also decreases the liability of moving the material when the cam is being rotated to clamp it in position. The carriage floor or shelf *s* is adjustably mounted to move forward and back on the horizontal support-pins *v*.

y indicates set-screws for clamping the floor *s* to the support *v*.

The springs *e* normally hold the carriage above the boring-bit, and in practical operation the sash stile or rail or other article to be bored will be laid in place upon the supporting device *s*, and the treadle *r* will be forced down to depress the carriage to bring the article down upon the cutter of the boring-bit, and the boring then takes place, the cuttings falling out by gravity, and thus clearing the hole which is being bored. Any suitable means may be provided for determining the length of the cut—that is to say, the depth of the hole bored. In the drawings the downward movement of the carriage is determined by the stroke of the treadle *r*, said stroke being long enough to allow the carriage to be depressed sufficiently to cause the boring-bit to bore the hole to the required depth. In practice the stile or other article to be bored will be placed on the carriage and will be slid along the carriage to be brought into boring position.

z z' indicate vertically-moving spring-operated retractible stops adapted to project upwardly above the level of the floor *s* to intercept the article to determine its position at the time of boring, thus to bore holes where desired. These stops may be of different forms, and preferably two forms of stops are provided for each carriage. In Fig. V, I have detailed the form of stop for use in the main body of the carriage. The stop there shown consists in a bolt 1, mounted to slide vertically in a case or barrel 2 and upheld by a spring 3, which is contained within the chamber of the case 2. Said case is furnished at its opposite ends with shoulders 4 5. The

shoulder 4 intercepts the shoulder 6 on the bolt, and the shoulder 5 supports the spring 4, which presses up against the shoulder 6 of the bolt. In the drawings the shoulder 5 is shown as a plug screwed into the case 2. Said case is screw-threaded at its upper end and is screwed into a screw-threaded hole 7 in the floor *s*, so that the stop-bolt 1 will project about a quarter of an inch, more or less, above the top of the floor *s*. Each spring 3 normally upholds the bolt 1 of its stop, and the several stops are arranged in a line parallel with the gage-bar *t*, which line intersects the extended axis of the boring-bit, so that when one hole has been bored the operator may lift the front end of the stile or other article and bring it onto the top of the stop *z* and allow its weight to rest thereon, thereby to depress the stop 85 to a level with the top of the floor *s*. Then the stile or other article will be slid along the floors until the hole which has just been bored in said stile or other article comes above the bolt 1, whereupon said bolt will be forced upward by the spring 3 and will enter the hole which has been bored in the article and will thus stop the article and prevent it from being pushed forward until it is again raised above the top of the bolt. The stops are arranged at such distances from the extended axis of the boring-bit as will correspond with the spaces required between the holes.

8 indicates a latch for holding the bolt 1 retracted. This latch is in the form of a link 10 slotted to receive the stem of the bolt 1 and having a thick portion 9 and a thin portion 10.

11 indicates a nut screwed on the stem of the bolt 1, and the link 8 is mounted on said stem between the nut 11 and the end of the case 2 in which the bolt 1 is contained. When the link 8 is adjusted to bring the thick portion 9 between the end of the case 2 and the shoulder formed by the nut 11, the bolt will be withdrawn to bring the upper end of the bolt flush with the top of the floor *s*. When the link is adjusted to bring the thin portion 10 thereof between the end of the case and the shoulder formed by the nut 11, the spring 3 will throw the bolt up into the position indicated in Fig. IV to stop the article to be bored.

The stop *z'* consists in a spring-arm of considerable length fastened to the end of the floor or shelf *s* and projecting therefrom and upbent at its outer end to project above the level of the floor *s*.

12 indicates sliding stops, respectively sliding in dovetail grooves 13 in the top of the floor *s* and which grooves extend at right angles to the gage bar or wall *t*. The purpose of these stops is to stop the article in a position or positions additional to that provided for the spring-carried stops. The stops are preferably made short, so that when they are drawn back out of the way they will not project so far beyond the edge of the table as to be in the way or be liable to be broken off. As they move freely in the grooves, they can

be quickly moved forward to engage with the piece of material being operated upon and as quickly moved back out of the way as soon as the first hole is bored and it is desired to 5 move the material lengthwise for the pin to enter the hole to hold the material for the next hole.

14 indicates a roller at the end of the floor s.

It is to be understood that the parts of the 10 carriage which are on opposite sides of the center are preferably duplicates of each other, so that the article can be slid along the carriage from either end toward the other end as required. The stops z are to be at such 15 distances from the extended axis of the boring-bit that when a hole has been bored and the article is slid along the stop will enter the hole and stop the article when it is in position for the boring of a second hole. These stops 20 may be arranged as required for the work to be performed by the machine. The sliding stops 12 are designed for stopping the stile of a door or window frame or other frame in which the stile of the unfinished door is longer 25 than required in the finished door—that is to say, it is customary with the stiles of doors, &c., to leave a projecting part which can be cut off in finishing the door—thus to remove any marring or splitting of the ends of the 30 stiles which may occur in handling the door before it is finished.

In practical work the operator will adjust the latches 8 to hold their appropriate bolts 1 in the required adjustment to form the stops 35 for the work in hand. If a door or window stile is to be bored, the sliding stop 12 will first be slid into position to stop the stile. Then the stile will be laid upon the floor s above the spring-supported stops z, which it will depress, and will be pressed against the gage-bar t and slid along until the end of the stile comes against the sliding stop 12. The stile will thereby be held in true position for boring the first dowel-hole. Then the stop 12 45 will be slid out of the way, and the stile will be slid along until the hole just bored comes above the bolt 1, which will then be thrown up into said hole, thus stopping the stile in position for the boring of the next hole. Then 50 the operator will again depress the carriage to bore the next hole. At each downward movement the operator will hold the cam u to clamp the stile.

The spring-bladed stop z' is adjustably and 55 detachably fastened to the shelf or floor s by a screw 15 and is adapted to support the ends of long door-stiles and the like and to stop the same appropriately. The upturned end of this stop may be adapted to enter the bored 60 hole the same as stops z.

16 indicates the wall or other support to which the slideway or frame p is fastened.

The gage-bar t is adjustable toward and from the boring-bit, so that it can be set to hold the stile or other article in position for 65 boring the hole where required.

17 indicates the floor of the room in which the machine is placed.

What I claim, and desire to secure by Letters Patent of the United States, is—

1. In a boring-machine, a support, a vertically-movable carriage thereon, laterally-projecting pins on the carriage, a table on the pins provided with a clamp, a guide adjustably mounted on the pins to the rear of the 75 table, the lower edge of which is perforated and provided with set-screws for engaging with the pins, and a rotary bit in position to project through the table.

2. In a boring-machine, a support, a vertically-movable perforated carriage thereon, provided with a socket at the rear of each perforation, a forwardly-extending pin removably secured in each socket, a table mounted on the forward ends of the pins, the 85 bottom of the table being provided with perforated projections for engaging with the pins, a guide to the rear of the table, the lower edge of which is perforated and provided with means for adjustably securing it 90 on the pins, and a rotary bit in position to project through the table.

3. In a boring-machine, a support, a vertically-movable carriage thereon, a flat table secured to the carriage and provided with a 95 series of perforations arranged in a line longitudinally thereof, a depressible stop in each of the perforations except the middle one, stops movable transversely across the table beyond the depressible stops, a clamp on the 100 table in front of the perforations, a guide adjustably secured to the rear of the table, and a rotary bit in position to project through the middle perforation.

4. In a boring-machine, a support, a vertically-movable carriage thereon, a perforated table connected with the carriage, the top of which is transversely grooved beyond the perforations, a stop slidably mounted in each of said grooves, a clamp on the table in front of 110 the perforations, a rotary bit in position to project through one of the perforations and retractable stops in the other perforations.

5. In a boring-machine, a support, a vertically-movable carriage thereon, a perforated 115 table connected with the carriage, the top of which is provided with transverse dovetailed grooves, the bottom of each of said grooves being recessed nearly to its front end, a dove-tailed stop slidably mounted in each groove, 120 the bottom of which is provided with a projection at its inner end to fit within said recess, a clamp on the table, a guide adjustably mounted to the rear of the table, and a rotary bit in position to project through one of 125 the perforations in the table.

6. In a boring-machine, a support, a vertically-movable carriage thereon, a table connected with the carriage, a cam mounted at the forward edge of the table, said cam comprising a lever provided with a semicircular head and pivoted at its forward end substan-

tially midway of the circular edge, said head being provided with a semicylindrical upwardly-extending projection, a guide adjustably mounted to the rear of the table, and a 5 rotary bit in position to project through the table.

7. In a boring-machine, a support, a vertically-movable carriage thereon, a perforated hanging-link, two yokes pivotally fastened 10 to the top of the carriage and to the perforated portion of the link respectively, springs for engaging with the yokes and yieldingly supporting the carriage, a table and an adjustable gage connected with the carriage, 15 and a rotary bit in position to project through the table.

8. In a boring-machine, a frame, pins projecting at right angles therefrom, a perforated table movably mounted on the outer 20 end of said pins, a vertical guide between the frame and the table, the lower edge of which is perforated and adjustably mounted on the pins, and a rotary bit adapted to be projected through the perforation of the table.

25 9. In a boring-machine, a vertically-movable table, the intermediate portion of which is perforated, a roller journaled across each end of the table, the top of which projects but slightly above the top of the table, and a 30 shouldered projection secured to one end of the table and extending out under the roller at that end.

10. In a boring-machine, the combination with a vertical rotary bit; of a vertically-reciprocating carriage furnished with a spring 35 extension which is provided with an upwardly-projecting stop for the purpose of supporting and stopping the edge of the article to be bored.

40 11. In a boring-machine, a perforated table, a boring-bit adapted to be projected through one of said perforations, retractable pins in the other perforations, and means

for retracting the pins and holding them retracted. 45

12. In a boring-machine, a perforated table, a boring-bit adapted to be projected through one of said perforations, a longitudinally-movable pin through each of the other perforations, and a cam for retracting each 50 pin and holding it in its retracted position.

13. In a boring-machine, the combination with a support for the article to be bored; of a barrel removably fastened to the support; a spring-operated bolt in said barrel; and 55 means for holding the bolt retracted against the force of said spring.

14. In a boring-machine, the combination with a support for the article to be bored; of a barrel fastened to said support; a spring- 60 actuated bolt in said barrel and projecting therefrom; and a stepped and slotted latch through which the projecting stem of the bolt extends; and means on the end of said stem to engage the latch for holding the bolt re- 65 tracted.

15. In a boring-machine, the combination with a support for the article to be bored; of a barrel fastened to the support and provided with an internal shoulder near one end 70 and being screw-threaded at the other end; a bolt playing in said barrel and furnished with a shoulder and with a stem; a plug fastened in the end of the barrel and through which the stem slides; a spring between the 75 plug and the shoulder of the bolt to throw the bolt outward; and means for holding the bolt retracted against the force of the spring.

In testimony whereof I have signed my name to this specification, in the presence of 80 two subscribing witnesses, at Los Angeles, California, this 18th day of March, 1901.

E. HIPOLITO.
